UNITED STATES PATENT OFFICE.

ALBERT C. FRENCH, OF PEOTONE, ILLINOIS.

DESIGN FOR A HEDGE-KNIFE.

SPECIFICATION forming part of Design No. 19,898, dated June 10, 1890.

Application filed May 16, 1890. Serial No. 352,096. Term of patent 14 years.

To all whom it may concern:

Be it known that I, ALBERT C. FRENCH, of Peotone, in the county of Will and State of Illinois, have invented and produced a new and original Design for Hedge-Knives, of which the following is a specification, reference being had to the accompanying drawings, forming part thereof.

Figure 1 is a perspective view of a blade showing my design, and Fig. 2 is a view of the back of the blade and the back of the handle to which it is attached.

The shank A of the blade is of a rectangular contour, and the marginal lines α and α' of the body are curved and eccentrically drawn, the outer line α being shortly curved at its junction with the inner line and both marginal lines join with the side lines of the shank. The marginal lines of the blade, at the point b , near the center, are carried later-

ally at an angle to the surface near the shank, imparting thereby a twisted contour B to the outer portion of the blade, and the sides of the blade, at the point thereon b' , are made to appear out of the plane of the shank-section. 25 The outline of the shank is broken upon one side by a lug-like figure D, and the handle E, to which the blade is represented as secured, is shaped to the contour of a parallelogram the greater portion of its length. One end e , 30 however, has the appearance of being enlarged and flared outward.

I claim—

A design for a hedge-knife, substantially as herein shown and described.

ALBERT C. FRENCH.
